DEVICE FOR MAINTAINING DIFFERENT TEMPERATURES IN REFRIGERATORS

Clinton Millman, Greenville, Mich.

Application January 4, 1950, Serial No. 136,743

9 Claims. (Cl. 62—103)

1

This invention relates generally to refrigerating structures and more particularly to a refrigerator which has compartments maintained at different temperatures from a single evaporator.

An object of this invention is to provide a new and improved arrangement for maintaining different temperatures in refrigerated compartments.

Another object of this invention is to provide a refrigerated cabinet in which sections are maintained at two different temperatures from a single evaporator.

Another object is to provide such a cabinet wherein the relative temperatures of the two compartments may be controlled.

Another object is to provide an evaporator in a refrigerated cabinet which may be conveniently defrosted without the defrost water going all over the cabinet.

Other objects of this invention will be apparent from the specification, the appended claims and drawings in which drawings:

Figure 1 is a front view, with the door open, of a refrigerator embodying the invention;

Fig. 2 is a view taken substantially along the line 2—2 of Fig. 1 and showing the baffle arrangement by which the relative temperatures in two portions of the cabinet are controlled;

Fig. 3 is a fractional perspective view looking upwardly at the baffle arrangement;

Fig. 4 is a view taken substantially along the line 4—4 of Fig. 2;

Fig. 5 is a view similar to Fig. 4 but showing the baffles in a different position;

Fig. 6 is an exploded perspective view of the baffles shown in Fig. 2;

Fig. 7 is a view of a modified form of invention in which the relative positions of the baffles are automatically controlled to maintain a desired temperature in the compartment cooled by the air passing through the baffles; and

Fig. 8 is a view taken substantially along the line 8—8 of Fig. 7.

Present day demands of housewives require a refrigerator which will maintain frozen foods properly frozen at a low temperature and also maintain other foods refrigerated at temperatures slightly above freezing temperatures. If such units are to be provided at a price which is attractive to home owners, they should be operated from a single condensing unit and from a single evaporator. Cabinets of this type which have been placed on the market are operated either from two evaporators in which a pressure difference is maintained therebetween by special

devices to cause them to operate at different temperatures or if from a single evaporator, the inside of the evaporator is used as the low temperature storage compartment.

5 The use of two evaporators involves a more or less complicated evaporating system in order to maintain the proper pressure and temperature differences between the two evaporators. When a single evaporator is used it must be relatively small so that it will not act to cool the nonfrozen storage compartment of the refrigerator below a desired temperature and thereby freeze up the foods or other comestibles stored in the nonfrozen compartment. Various schemes have 10 been tried for enlarging the internal storage capacity of the evaporator but these have not been completely successful since the difference in temperature between the two compartments was too widely variable as a function of change in the ambient temperature surrounding the cabinet.

15 My invention generically contemplates the use of a frozen storage compartment of any desired size which is directly cooled by the refrigerant and a nonfrozen storage compartment which is cooled by circulating air cooled by the refrigerant and in which the rate of circulation is restricted to that necessary to maintain the desired temperature in the nonfrozen storage compartment. In its more specific form, the invention provides 20 for inserting a two part baffle structure between an evaporator defining a frozen storage compartment in the top portion of a cabinet and the nonfrozen storage space in the lower portion of the cabinet. The baffle as shown comprises two interfitting and relatively movable members provided with spaced louvers or apertures separated by sloping imperforate wall sections. The apertures or louvers are relatively spaced in the two members so that upon relative movement of the members, the apertures of the members may all be brought into alignment for relatively unrestricted flow of air through the baffle or out of alignment for restricted flow of air therethrough and for preventing defrost water from falling into the nonfrozen storage compartment.

25 Referring to the drawings by characters of reference, the numeral 1 indicates generally a refrigerator cabinet having a door 2 for opening and closing an access opening 4 whereby comestibles may be placed within and removed from the cabinet 1. The cabinet 1 comprises the usual outer and inner shells 6 and 8, the space between which may be filled with an insulating material, not shown. A suitable throat covering or breaker 30 strip 10 is provided to close the space between the

shell or liner 8 and outer wall 6 so that the cabinet will have a pleasing appearance. The lower portion of the liner 8 defines a nonfreezing refrigerated storage portion 12. An evaporator 14 defining a freezing storage portion is positioned within the upper portion of the shell 8 and comprises a five sided rectangular box provided with an access door 16 for closing the open front and which door may be hinged as at 18 adjacent its lower edge portion to the shell 8. One or more of the five walls may have in heat exchange relation therewith refrigerant containing reservoirs or passageways in which evaporating liquid refrigerant is contained for extracting heat from the interior of the cabinet 1. Such passageways may be conveniently provided by a length of sinuously arranged tubing 22 which is suitably secured in heat exchange relation to the evaporator walls as by soldering, brazing, or otherwise. One end of this tubing 22 is connected to a refrigerating condensing unit through any usual flow controlling device in the usual manner whereby a controlled flow of liquid refrigerant is supplied to the tubing 22 wherein it is vaporized thereby absorbing heat from the evaporator 14. The other end of the tubing 22 is connected to the condensing unit whereby the vapor is returned to the condensing unit for condensation and a subsequent recirculation.

A usual thermostat 24 carried in the upper breaker strip section 10 has a temperature responsive element not shown responsive to the temperature of the upper evaporator 14 or to the interior temperature thereof whichever may be desired and acts to stop and start the condensing unit not shown in order to maintain the evaporator 14 at the desired temperature.

A pair of baffle members or plates 26 and 28 are arranged substantially horizontally of the cabinet 1 below the evaporator 14 but tilt slightly rearwardly for a purpose to be set forth more clearly hereinafter. The front edge portion of the bottom wall 20 of the evaporator 14 rearwardly of the door 16 is downturned and reversely bent to provide a pocket 29 for receiving a downturned lip 30 of the lower baffle plate 26. The baffle plate 26 comprises a sheet of material which has been formed to provide a series of parallelly raised portions or crests 33 extending substantially completely from front to back of the plate 26 and separated by parallel troughs 32. The raised portions have longitudinal apertures 34 which extend substantially completely throughout the lengths of the crests 33. The baffle plate 26 has a peripheral flange 36 extending substantially completely therearound. The portion 33 of the flange 36 along the front edge of the baffle plate 26, extends upwardly beyond the rest of the flange 36 and is partially rebent upon itself to provide the lip 30.

The side walls of the liner 8 adjacent the rear wall thereof are provided with outwardly extending abutments 40 which underlie and serve to support a rear portion of the lower baffle plate 26. Preferably the abutments 40 are located vertically with respect to the pocket 29 so that when the lower baffle plate 26 is resting in the pocket and on the abutments 40, the rear edge portion of the baffle plate 26 is slightly lower than the front portion so that any water collecting in the troughs or channels 32 will flow to the rearward portion of the baffle plate 26 and flow therefrom through an outlet 42 into a suitable container (not shown) which may be placed below this outlet 42, or, if desired, the outlet 42 may be con-

nected by means of a conduit member (not shown) and discharged externally of the refrigerator. This exterior discharge may be either into a container placed for the purpose, a conveniently located drain, or, if desired, may be conducted to the condensing unit, the heat of which will serve to vaporize this water into the surrounding atmosphere.

An upper baffle member 28 is provided with 10 downturned side flanges 52 and downturned diagonally extending rear and front flanges 54 and 56. The flanges 54 and 56 are adapted to rest on the bottom of baffle plate 26 adjacent the front and rear portions of the peripheral flange 36 to 15 position the upper baffle member 28 for sideways sliding movement of the member or plate 28 relative to the lower baffle plate or member 26. The upper baffle member 28 is of less width than the lower baffle member 26 whereby it may be 20 moved sideways by means of the handle 58 to control flow of air therethrough and to properly direct the defrost water from the evaporator 14.

The upper baffle member 28 is provided with a series of depressed troughs or valleys 60 which 25 are apertured as at 62 and which extend parallel with each other and are equally spaced with the crests of the plate 26. In one position of the upper baffle member 28 the apertures 62 overlie the apertures 34 of the lower baffle member 26 30 as shown in Fig. 4 to permit a high rate of air circulation from the evaporator 14 to the lower compartment 12. When the upper baffle member 28 is in its other position the apertures 62 overlie the channels 32 whereby only restricted air 35 flow will be possible from the evaporator 14 to the lower storage compartment 12. This position of the baffles is shown in Fig. 5 and is the position to which the baffles are moved during defrosting of the evaporator 14.

The dimensions of the baffle members 26 and 28 are preferably so chosen with respect to the cross sectional area of the liner 8 at this location to provide an upflow air passageway 64 between the two opposite side walls and the rear wall of the liner 8 and the baffle members 26 and 28. In this manner air from the compartment 12 which will of course be warmer adjacent the walls of the liner 8 flows upwardly 45 through the passageway 64 into heat exchange relation with the evaporator 14 and then flows 50 downwardly through the apertures 34 and 62 to cool the compartment 12. The rate of such circulation will be determined by the resistance offered by the members 26 and 28 which is variable depending upon the degree of alignment 55 of the apertures 34 and 62.

It will be seen that with the baffle members 26 and 28 positioned as shown in Fig. 5, as the frost on the evaporator melts and drips in the 60 form of water onto the upper baffle member 28 it will flow from the apertures 62 in the valleys 60 downwardly through the apertures 62 and into the channels or valleys 32 along the channels 32 to the rear portion of the baffle member 26 and 65 outwardly through the drain opening 42. Since the evaporator 14 is, during operation, maintained at a temperature substantially below 32° F. to hold the freezing compartment low, defrosting will occur only when desired and the baffle members 26 and 28 may at these instances be moved to the defrosting position shown in Fig. 5.

During normal operation of the refrigeration apparatus the control 24 is turned to maintain the desired temperature within the evaporator 75 14 and the upper baffle member 28 is positioned

relative to the lower baffle member 26 to provide for the proper rate of air flow from the evaporator 14 into the lower compartment 12 whereby the lower compartment is maintained at the desired temperature. If the temperature of the evaporator 14 is lowered it may be necessary to restrict air flow through the baffle members 26 and 28 so that the temperature in the space is not brought below the desired temperature. Conversely as the temperature of the evaporator 14 is raised, it may be necessary to permit a greater flow of air through the baffle members 26 and 28 by moving the member 28 in a direction from the position shown in Fig. 5 toward that shown in Fig. 4. Since the heat leakage outwardly from the compartment 12 will vary as the difference between the temperature of the compartment 12 and the ambient temperatures surrounding the cabinet 1, it may be necessary to occasionally adjust the relative position of the baffle members 26 and 28. Such an adjustment will most likely be necessary only if excessive changes in ambient temperature occur.

Referring to Fig. 7 and Fig. 8 there is shown therein an automatic arrangement for adjustably positioning the upper baffle member 28 in accordance with temperatures existing in the compartment 12. This apparatus comprises a sealed pressure system comprising a conduit 88 connected at the one end with a bulb 82 containing a quantity of temperature sensitive fluid and having its other end connected to a bellows member 84. One end of the member 84 is fixedly secured as by a bracket 86 and its other end comprises a movable wall 88, the position of which will vary in accordance with the pressure communicated to the bellows member from the bulb 82. The movable wall 88 is pivotally connected to a lever arm 90 fulcrumed on a pin 92 and extending into operative engagement with a downturned arm 94 which may be the handle 58 or a separate arm provided for this purpose. Movement of the arm 90 by the bellows member 84 is opposed by a spring 96 and provides a substantially fixed position of the lever 90 for a given pressure within the bellows member 84. This relationship between pressure in the bellows member 84 as reflected by the bulb 82 and the position of the arm 90 may be controlled by means of an adjusting screw 98 which acts to vary the force exerted by the spring 96.

As the temperature within the compartment 12 and of the bulb 82 increases the movable wall 88 of the bellows member 84 will move the arm clockwise as seen in Fig. 8 thereby moving the top baffle 28 in a direction toward the right as seen in Fig. 4 and Fig. 5. If the temperature in this space 12 decreases, the pressure in the bellows member 84 will decrease and the spring 96 will rotate the lever counterclockwise (Fig. 8) and move the top baffle member 28 to the left. Movement of the baffle member 28 toward the right from the position shown in Fig. 5 toward that shown in Fig. 4 permits more and more flow of cooling air from the evaporator 14 to the compartment 12 while left movement of the upper baffle member 28 from the position of Fig. 4 toward the position of Fig. 5 acts to decrease the flow of air from the evaporator 14 to the compartment 12. The apparatus shown in Fig. 8 is therefore operable to automatically control the position of the upper baffle member 28 to provide for a substantially constant temperature within the compartment 12. For defrosting purposes the pin 92 could be removable to permit manual

movement of the baffle members to the positions shown in Fig. 5. If desired a hook or other stop member could be used to hold the member 28 against the force of the bellows member 84.

5 The bottom wall 20 of the evaporator 14 is provided with one or more drain holes 100 which overlie the baffle members 26 and 28 and permit flow of defrosting water outwardly of the evaporator 14 during a defrosting operation to pass downwardly on the baffle member and then through the drain hole 42. The bottom wall 20 of the evaporator also slopes downwardly toward the rear of the cabinet so that any defrost water which collects within the evaporator will flow outwardly through the apertures 100 rather than outwardly through the front access opening.

What is claimed and is desired to be secured by United States Letters Patent is as follows:

1. In a refrigerator, a cabinet having vertical walls defining a storage space, an evaporator in the upper portion of said space and having a downwardly depending upturned hooklike element, a first baffle extending transversely of said walls and comprising a member having a bottom wall surrounded by a peripheral flange extending upwardly above the plane of said bottom wall, one portion of said flange having a downturned hooklike portion receivable within said element to support said first baffle, a second baffle comprising a top wall having spaced downturned portions seating on said first baffle and supporting said top wall in spaced relation to and above said bottom wall, said bottom wall being undulated to provide crests and valleys, said bottom wall being apertured at at least some of said crests, said top wall being movable relative to said bottom wall and having an aperture aligned with said bottom wall aperture when said members are in a first relative position and disaligned when said members are in a second relative position.

2. The combination of claim 1 in which said cabinet is provided with an access opening, said flange hooklike portion is located adjacent said access opening, the longitudinal axes of said crests and valleys extend rearwardly of said cabinet from said opening, and said valleys slope rearwardly of said cabinet.

3. In a structure of the character described, a first baffle comprising a member having a bottom wall surrounded by a peripheral flange extending upwardly from said bottom wall, one portion of said flange having a downturned hooklike portion receivable within said element to support a supporting first baffle, a second baffle comprising a top wall having spaced downturned portions seating on said first baffle and supporting said top wall in spaced relation to and above said bottom wall, said bottom wall being undulated to provide crests and valleys, said bottom wall being apertured at at least some of said crests, said top wall being movable relative to said bottom wall and having an aperture aligned with said bottom wall aperture when said members are in a first relative position and disaligned when said members are in a second relative position.

4. In a refrigerator, a cabinet having vertical walls defining rear and side walls of a storage space, a movable closure defining the front wall of said cabinet, an evaporator located in the upper portion of said space and having a bottom wall, an upturned hook member held in fixed position in said cabinet and positioned below said bottom wall adjacent said front wall, sup-

ports carried in fixed position within said cabinet adjacent said rear wall; a baffle structure comprising first and second baffle members, said first member being panlike and having a bottom wall with an upwardly extending peripheral side wall about the entire periphery of said bottom wall, a portion of said peripheral wall having a downturned lip receivable in said hook member to support the forward portion of said structure, said first baffle member extending toward said rear wall into overlying relationship with said supports whereby the rearward portion of said baffle structure is supported in said cabinet, said second baffle member having spaced portions extending downwardly therefrom for sliding engagement on said first baffle whereby said second baffle member is supported by said first baffle member, each said baffle member having an aperture therethrough, said baffle members being relatively movable whereby said apertures may be brought toward and away from registering positions, the peripheral portions of said first baffle aperture being spaced upwardly from said bottom wall.

5. In a refrigerator, a cabinet having vertical walls defining rear and side walls of a storage space, a movable closure defining the front wall of said cabinet, an evaporator located in the upper portion of said space and having a bottom wall, an upturned hook member held in fixed position in said cabinet and positioned below said bottom wall and adjacent said front wall, supports carried in fixed position on said side walls adjacent said rear wall, a baffle structure comprising first and second baffle members, said first baffle member being panlike and having a bottom wall with an upwardly extending peripheral side wall about the entire periphery of said bottom wall, a portion of said peripheral wall having a downturned lip receivable in said hook member to support the forward portion of said structure, said first baffle member extending toward said rear wall into overlying relationship with said supports whereby the rearward portion of said baffle structure is supported in said cabinet, said second baffle member having spaced portions extending downwardly therefrom for sliding engagement on said first baffle bottom wall whereby said second baffle member is supported by said first baffle member, each said baffle member having an aperture therethrough, said baffle members being relatively movable whereby said apertures may be brought toward and away from registering positions, the peripheral portions of said first baffle aperture being spaced upwardly from said bottom wall and those of said second baffle aperture being spaced downwardly from said top wall.

6. In a baffle structure, a first baffle member comprising a bottom wall having an upstanding side wall extending completely about the periphery of said bottom wall, a second baffle member comprising a top wall and spaced downwardly extending supports seating on said bottom wall for supporting said top wall in elevated relation to said bottom wall, said bottom wall being undulated to provide crests and valleys, said crests being of less height than the spacing between said member walls, at least some of said crests being apertured, said members being relatively movable, said top wall being apertured such that

at one relative position of said members said apertures are aligned and at a second relative position of said members said apertures are disaligned.

5. In a structure of the character described, a pair of undulated members providing crests and valleys, said crests and valleys of one of said members being equally spaced with said crests and valleys of the other of said members, at least some of said crests of said one member being apertured and at least some of said valleys of said other member being apertured, said one member being provided with a peripheral flange extending upwardly above said one member valleys, said other member being provided with tabs seating on the bottom wall of said one member adjacent portions of said flange for supporting said members for guided relative movement.

8. In a structure of the character described, a pair of undulated members providing spaced crests and valleys, one of said members being provided with spaced downwardly extending supports, the other of said members being provided with means for receiving said supports and co-operable with said supports to support said members for limited relative movement thereof, at least some of said crests of said other member and at least some of said valleys of said one member being apertured, said other member further including a flashboard-like portion extending upwardly therefrom, said other member having means positioned below the top surface of said flashboard-like portion for collecting liquids which may accumulate in said other member valleys.

9. In a structure of the character described, a pair of undulated members providing spaced crests and valleys, one of said members being provided with spaced downwardly extending supports, the other of said members being provided with means for receiving said supports and co-operable with said supports to support said members whereby the bottom surfaces of said one member valleys are spaced above the top surfaces of said other member crests to permit relative movement of said members without engagement of said crests and said valleys, at least some of said crests of said other member and at least some of said valleys of said one member being apertured, said other member further including a flashboard-like portion extending upwardly therefrom, said other member having means positioned below the top surface of said flashboard-like portion for collecting liquids which may accumulate in said other member valleys.
